UNITED STATES PATENT OFFICE.

JOHN CHRISTIAN, OF SAN JOSÉ, CALIFORNIA.

BLANK FOR FORMING THRASHING-MACHINE-CYLINDER TEETH.

SPECIFICATION forming part of Letters Patent No. 308,135, dated November 18, 1884.

Application filed January 14, 1884. (No model.)

To all whom it may concern:

Be it known that I, JOHN CHRISTIAN, of San José, county of Santa Clara, and State of California, have invented an Improvement in 5 Blanks for Forming Thrashing-Machine-Cylinder Teeth; and I hereby declare the following to be a full, clear, and exact description thereof.

My invention relates to certain improvements in the construction of teeth for thrashing-machine cylinders; and it consists, mainly, 10 in the formation of the blanks for the steel fronts, which are to be welded to iron teeth to increase their durability, and in a means 15 for retaining the rough blanks from which the tooth and front are formed in contact until they are welded securely by a drop-hammer and dies.

Referring to the accompanying drawings for 20 a more complete explanation of my invention, Figure 1 is a view of the rough strip of steel with lug or projection shaped and ready to be attached to the tooth-blank. Fig. 2 is a view 25 showing the blanks in position to be welded and shaped. Fig. 3 is a view of the completed tooth.

In the construction of iron teeth for the cylinders of thrashing-machines it has been found desirable and necessary to make the fronts of 30 the teeth of steel, so as to reduce the wear and render the teeth more durable.

My invention relates to the formation of the blanks A of steel, which are to be applied to the tooth-blanks, so that the two may be 35 welded and struck into form by one blow of the die. These steel blanks A are made by means of a die having one end much shallower than the other and having a hole or depression in it. The pieces of steel, cut to the proper 40 length and heated, are laid in this die, and a single blow of the hammer shapes them, drawing one end to a thin edge, and at the same

time forming a short pin or projection, B, upon 45 the end. When the iron tooth-blank C is heated, the pin is readily forced in the soft metal by a blow, and the two parts are held together until they can be heated and welded. The blank A is made of such a length that when it is laid upon the blank C and the two 50 are laid in the die by which the tooth is to be shaped the point or thin end of the steel will reach a point just where the shank of the tooth will have its shoulder formed, and the two being 55 suitably heated, the blow of the hammer welds and shapes the whole tooth simultaneously. The steel face is thus welded to the front of the tooth, and extends down to the point where the shank commences, the shank upon which the screw-thread is cut, and which 60 passes through the cylinder-bar, being formed of iron.

It will be seen that the teeth may be hardened or tempered at the same heat.

Having thus described my invention, what I claim as new, and desire to secure by Letters Patent, is—

1. The steel blank A, to be applied to the front of a thrashing-cylinder tooth, said blank having one end drawn thinner than the other, and provided with a pin or lug by which to 70 secure it to the tooth-body, substantially as herein set forth.

2. The steel blank A, to be applied to the front of a thrashing-cylinder tooth, said blank being thinner at one end than the other, and 75 provided with a lug or pin upon one end, substantially as and for the purpose set forth.

In witness whereof I have hereunto set my hand.

JOHN CHRISTIAN.
